UNITED STATES PATENT OFFICE

LLOYD C. DANIELS, OF CRAFTON, PENNSYLVANIA, ASSIGNOR TO THE SELDEN COMPANY, OF PITTSBURGH, PENNSYLVANIA, A CORPORATION OF DELAWARE

PRODUCTION OF DIBENZANTHRONE

No Drawing.

Application filed April 4, 1929. Serial No. 352,605.

This invention relates to the production of dibenzanthrone compounds and more particularly to dibenzanthrone and isodibenzanthrone.

Dibenzanthrone has been produced in the past by caustic potash fusion of benzanthrone in the presence of a reducing agent, usually dextrin, and isodibenzanthrone has been produced by fusions of chlorbenzanthrone in alcoholic caustic potash. The fusion processes for producing dibenzanthrone and isodibenzanthrone have been open to a number of serious disadvantages. In the first place the amount of caustic potash required in the fusions is very high, amounting normally to from ten to twelve times the theoretical amount required to react. The large excess has been necessary in order to produce a satisfactorily fluid melt. In the case of the isodibenzanthrone fusion a large excess of alkali over that theoretically required has also been necessary because of the low boiling point of alcohol which necessitated a large excess in order to maintain sufficient alcohol in the liquid state in the melt. The excess alcohol has to be recovered and this recovery is not complete. The prior processes for making dibenzanthrone also produced large amounts of impurities, the normal yield of dye being not more than 50% based on the benzanthrone used, which not only means a loss of benzanthrone but also increases the cost of transforming dibenzanthrone into the nitrocompound in which form it is usually sold.

According to the present invention dibenzanthrone fusions are carried out in the presence of heterocyclic carbonyl compounds in which are included aldehydes, alcohols, ketones, etc. Liquid carbonyl compounds containing the furane or hydrogenated furane nucleus, such as furfural and its homologues, furfuryl alcohol, liquid condensation products of furfural and acetone, or methyl ethyl ketone, etc., constitute the preferred class under the present invention, furfural being particularly effective in the dibenzanthrone fusion.

When the reducing agents of the present invention are used a much smaller amount is

generally sufficient, the amount of caustic potash can be greatly decreased, particularly with the preferred liquid reducing agents, and the products obtained show higher percentages of dye than is obtainable in the prior processes. The improvement is especially marked in the dibenzanthrone fusion using furfural. Since the chief costs in the process are the caustic potash and benzanthrone, the reduction in the amounts of both of these ingredients, and especially the marked reduction possible in the amount of caustic potash when using the preferred liquid solvents of the present invention, represent very great savings, which savings are still further increased when the dibenzanthrone products are to be used for the production of nitrodibenzanthrone as in this case in addition to the lower cost of the dibenzanthrone compound further savings in reagents, especially nitrating mixture and hydrosulfite used in reducing the crude nitro-product, are effected by reason of the greatly decreased percentage of non-volatile impurities produced in crude dibenzanthrone product.

The following specific examples give a few typical embodiments of the present invention with some of the preferred class of solvents, but the invention is in no sense restricted to the details therein set forth, and particularly it should be noted that the invention is not limited to fusions in which the amount of caustic potash is decreased over the standard of 5 parts to 1 of benzanthrone or chlorbenzanthrone. In some cases, it is desirable to use larger amounts of caustic potash and to obtain only the advantages of higher purity of product. Such processes are, of course, included in the present invention as well as those in which the advantages of improved yield are combined with a reduction in the amount of caustic potash used and which processes represent usually the greatest savings and constitute the preferred embodiments of the invention. The parts are parts by weight.

Example 1

100 parts benzanthrone are ground with 5 parts of furfural and added slowly at 220° 100

C. to a mixture of 300 parts of 90% caustic potash and 2½ parts of furfural. After the addition of the benzanthrone the mixture is heated to 240° C. for 45 minutes, after which 5 the dibenzanthrone is isolated by pouring the melt into water, oxidizing the leuco-compound with air and filtering in the usual manner. The product obtained is of superior quality giving brighter and stronger 10 dyeings and the yield is better than when carbohydrates are used in the standard fusion and a notable saving is effected by reason of the fact that only three-fifths as much caustic potash is used as that ordinarily required. 15 The amount of furfural may vary and where an extremely fluid melt is desired the amount of furfural may be doubled.

Example 2

20 100 parts of benzanthrone are ground together with 5 to 10 parts of furfuryl alcohol and added slowly at 220° C. to a mixture of 300 parts of 90% caustic potash and from 2½ to 5 parts of furfuryl alcohol. After 25 adding the benzanthrone the mixture is heated to complete the fusion, as described in Example 1, an excellent dibenzanthrone compound being obtained.

Example 3

30 100 parts of chlorbenzanthrone are fused in a mixture containing 300 parts of 85-90% KOH and 120 parts of furfural. If desired, part of the furfural may be mixed with the 35 chlorbenzanthrone and added to the caustic potash and the remainder of the furfural. The fusion is carried out under a reflux condenser at the ordinary temperatures used in alcoholic fusions of chlorbenzanthrone. 40 Excellent yields of isodibenzanthrone are obtained and as the furfural is consumed and it is unnecessary to use an excess no recovery costs are entailed as is the case when alcohol is used as a reducing agent and flux. The 45 amount of caustic potash is only about three-fifths that normally required and represents a very notable saving.

What is claimed as new is:

1. A method of fusing a benzanthrone compound to produce a dibenzanthrone compound, which comprises fusing a benzanthrone compound with caustic alkali in the presence of a liquid carbonyl compound containing the furane nucleus.
- 55 2. A method according to claim 1, in which the amount of caustic potash used does not exceed three parts to one of the benzanthrone compound.
3. A method of fusing a benzanthrone compound to produce a dibenzanthrone compound, which comprises fusing the benzanthrone compound with caustic alkali in the presence of furfural.
- 60 4. A method according to claim 3, in which the amount of caustic potash used does not

exceed three parts to one of the benzanthrone compound.

5. A method of fusing benzanthrone to produce dibenzanthrone, which comprises fusing the benzanthrone with caustic alkali 70 in the presence of a liquid carbonyl compound containing a furane nucleus.

6. A method according to claim 5, in which the amount of caustic potash used does not exceed three parts to one of the benzanthrone. 75

7. A method of fusing benzanthrone to produce dibenzanthrone, which comprises fusing the benzanthrone with caustic alkali in the presence of furfural. 80

8. A method according to claim 7, in which the amount of caustic potash used does not exceed three parts to one of the benzanthrone compound.

9. A method of preparing isodibenzanthrone, which comprises fusing a halogenated benzanthrone with caustic potash in the presence of a liquid carbonyl compound containing the furane nucleus. 85

10. A method according to claim 9, in 90 which the amount of caustic potash is not more than three parts to one of halogenated benzanthrone.

11. A method of preparing isodibenzanthrone, which comprises fusing a halogenated 95 benzanthrone with caustic potash in the presence of furfural.

12. A method according to claim 11, in which the amount of caustic potash is not more than three parts to one of halogenated 100 benzanthrone.

Signed at Pittsburgh, Pennsylvania, this 29th day of March, 1929.
